UNITED STATES PATENT OFFICE.

SILAS CORDES, OF BOISE, IDAHO.

HEADLIGHT ATTACHMENT.

Application filed January 23, 1926. Serial No. 83,240.

This invention relates to a device for controlling the rays of an automobile headlight or spotlight.

The object of this invention is to construct a device capable of attachment to the conventional headlight or spotlight of a motor vehicle of such a character that the rays from the lights will be projected in a definite direction and within a confined field.

Another object of this invention is to provide a device of the character noted which will embody a construction of artistic and ornamental form which can be cheaply manufactured for application to any type of lamp.

Other objects will more clearly herein-after appear by reference to the specification and attached drawings wherein like numerals of reference designate corresponding parts throughout the several views, in which:

Figure 1 is a side elevation of a lamp showing one form of the invention in position in section;

Figure 2 is a front elevation of the device shown in Figure 1.

Figure 3 shows in elevation a modified arrangement of the partitions;

Figures 4 and 5 are similar views where-

in the partitions are formed of sheet metal. As shown in Figure 1, a cylindrical body of sheet metal is provided formed at its front edge with a plurality of spaced projections 1 upon which the transparent slats or partitions 2 are arranged. These slats are made of suitable glass and may be of any desired color found convenient to soften the rays from the lamp. The front edge of the cylinder is bent inwardly to form a flange

4 and at intermediate points within the cylinder are the lugs or extensions 5 which engage the inner faces of the slats to retain the same in fixed position with relation to the front flange 4. For spacing the slats 2 at their inner ends, the inwardly projecting portions 5' are provided formed integral with the lugs 5. The projections 1 abut against the flange 4.

Obviously, the width of these partitions 50 or slats 2 will control to a large extent the projection of the light rays and with this in mind the upper slats are made of gradually increased widths. By this arrange-

ment the rays from the upper portion of the lens of the lamp which have a tendency to 55 be more glaring because of their elevated positions are relatively more confined.

The portion of the cylindrical body which extends rearward of the partitions may be of any desired diameter to facilitate the 60 application to a lamp body and when applied thereto the lugs 5 act as stops to position the same.

In Figure 3 a modification is shown in elevation wherein cross-slats are provided 65 made from substantially the same material as the partitions shown in Figure 1. In Figures 4 and 5 these partitions or slats are shown in variegated form constructed of sheet metal and designed to present an ornamental or artistic appearance and at the same time provide for the control of the rays as in the other form.

Obviously, numerous designs can be presented involving the same principle and accomplishing the same result to different degrees. Also any suitable means may be provided for securing the present attachment in position on a lamp and the rear portion of the cylinder which encircles the front of 70 a lamp may be modified as deemed necessary to permit application.

What I claim as my invention and desire to secure by Letters Patent of the United States is:

1. In a ray control device, a cylindrical body formed with a flange at its outer edge, a plurality of stops projecting from said body at intermediate points in its circumference, a plurality of transparent partitions 85 arranged between said stops and said flange and spacing means for said partitions.

2. In a ray control device, a cylindrical body formed with a flange at its outer edge, a plurality of stops projecting from said body at intermediate points in its circumference, a plurality of partitions arranged between said stops and said flange, and spacing means for said partitions including spaced extensions projecting from said 95 stops, and other spaced extensions abutting against the flange.

In testimony whereof I hereunto affix my signature,

SILAS CORDES.
